United States Patent Office

Des. 222,407
Patented Oct. 19, 1971

222,407

CARRYING CASE FOR A CAMERA OR THE LIKE

Vincent F. Lang, Rochester, N.Y., assignor to Eastman Kodak Co., Rochester, N.Y.

Filed Nov. 9, 1970, Ser. No. 25,904

Term of patent 14 years

Int. Cl. D3—01

U.S. Cl. D87—5

FIG. 1

Des. 222,407

PAGE 2

FIG. 3

FIG. 1 is a front perspective view of a carrying case for a camera or the like showing the side and top of my new design;

FIG. 2 is a rear perspective view showing the bottom and other side thereof; and

FIG. 3 is a side elevation thereof in an open condition.

I claim:

The ornamental design for a carrying case for a camera or the like, as shown.
